UNITED STATES PATENT OFFICE

MAXWELL I. MATHEWSON, OF PROVIDENCE, RHODE ISLAND, ASSIGNOR TO BROWN & SHARPE MANUFACTURING COMPANY, A CORPORATION OF RHODE ISLAND

GRINDING MACHINE

Original application filed July 19, 1927, Serial No. 206,917. Divided and this application filed December 24, 1930, Serial No. 504,553.

The present invention relates to grinding machines, and more particularly to means for protecting certain of the parts from the water or emulsion which is necessarily used in the 5 grinding operation. The invention, as herein disclosed, is embodied in a type of machine in which the grinding wheel is mounted on a carriage to move toward and away from the work, and the work is mounted on a 10 work supporting table movable back and forth longitudinally of the grinding wheel spindle. In order to catch the water or emulsion which is poured onto the point of contact of the grinding wheel and the work, a trough 15 is provided between the wheel spindle carriage and the work table.

In carrying out the present invention, a novel and improved arrangement of water guards has been provided to protect the wheel 20 spindle carriage ways and other parts of the machine from contact with the grinding emulsion. These guards are simply and efficiently designed to conform to the contours of the machine, to extend adequately over 25 the surface to be covered as the wheel spindle carriage is moved away along its slide, and to collapse readily into a small space as the carriage is returned to its limiting position at the near end of the slide.

30 The several features of the invention will be readily understood by one skilled in the art from the following description taken in connection with the accompanying drawings in which Fig. 1 is a view in right side 35 elevation of the machine, only so much thereof being shown as is necessary to show the connection of the present invention therewith; Fig. 2 is a more detailed view taken in left side elevation on a large scale; and Fig. 40 3 is a similar view in right elevation on a large scale.

For a more complete disclosure of the machine, and for a complete description thereof, reference may be had to the inventor's pending application, Serial No. 206,917, filed July 19, 1927, of which the present application is a division.

45 Referring to the drawings, the machine illustrated comprises a frame 12 on the front portion of which is mounted a work support-

ing table 14, which is adapted for transverse movement on ways 16, and is provided with a head stock 18, and a foot stock. A rotary grinding wheel is indicated at 22, secured to a wheel spindle 24 on the wheel spindle carriage 26, which is mounted on ways 28 on the rear portion of the frame to slide towards and away from the work. The grinding wheel spindle 24 is driven from a drive shaft 30 mounted in the base of the machine by means of a belt 32 which passes over a pulley 34 on the wheel spindle 24 and under the idler pulley 36 and take-up pulley 38 in the base of the machine and around a pulley 40 on the drive shaft 30. An electric motor 42 acting 55 through a belt 44 supplies the driving impetus to the drive shaft 30. A water trough 46 is formed in the machine frame 12 between the work support and the wheel spindle carriage to drain off the water which is continuously poured over the work during the grinding operation.

60 In grinding metal surfaces with grinding wheels having high peripheral speeds, it is necessary to keep a continual flow of water, or some grinding emulsion, on the point of contact between the metal and the grinding surface to prevent overheating of the parts and to insure a smooth and efficient abrading action. In order to conserve the use of 65 this water or grinding emulsion, a water trough is formed in the machine frame 12 between the work supporting table 14 and the wheel spindle carriage 26 to collect and draw off the emulsion. Due to the corrosive action of the water, and more particularly of 70 ingredients such as caustic soda in the grinding emulsion on the highly polished operating portions of the machinery, and due to the injurious effects of the water or emulsion 75 on the oil film protecting the bearing surfaces in the machine, it has been found necessary to shield very carefully the various portions of the machine which are likely to come 80 in contact with the emulsion. It is of the greatest importance to protect adequately the 85 bearing surfaces of the ways 16 and 28 on which the work supporting carriage and the wheel spindle carriage are respectively 90 mounted to slide. To this end, a laterally 95 100

and upwardly extending slot 48 is provided on each side of the work supporting table 14 and is adapted to receive a corresponding flange or plate 50 formed on corresponding portions of the frame 12 adjacent to the ways 16. In this manner, any spattering of water or emulsion is effectively prevented from reaching any of the operating parts of the machine located within or beneath the work 10 supporting table.

In order to protect the ways 28 for the wheel spindle carriage 26 and other operating parts as, for instance, the driving belt, which would be exposed by the movement of 15 the carriage, flexible guards have been provided which effectively fill the space between the ends of the wheel spindle carriage and the base, to cover up the ways and underlying parts, as these are uncovered by the retracting 20 movement of the grinding wheel carriage, these guards being so designed that they fold up into a comparatively small compass as the wheel spindle nears the end of its travel in either direction.

25 With the present construction of the machine, which includes a passageway for the lubricating medium and a housing for the cross feed screw, it has been found impracticable to provide a single guard member to 30 protect the forward end of the ways, since such a member would necessarily be comparatively large, and would extend well into the water trough as the wheel spindle carriage reaches the limit of its forward movement, bringing the guard into interference 35 with the housings for the feed screw and oil conduit.

In carrying out the several features of the present invention, a comparatively short upwardly extending guard 52, which extends laterally of the machine across the width of the wheel spindle carriage, is pivoted at 54 on the machine frame 12, and is adapted to rest against the forward ends of the ways 28 for 40 the wheel spindle carriage. Overlying the guard 52 is a second guard 56 which is hung from pivots 58 formed on the wheel spindle carriage 26. With the wheel spindle carriage in its foremost position, in contact with the 45 work, the guard 56, as best shown in Fig. 1, extends downwardly to a point substantially opposite the pivot 54 of the guard 52, just above the trough 46. The edges of the guard 56 are turned over to give additional protection 50 to the exposed machine parts. A tension spring 60, secured at one end of a pin 62 on the machine frame and at its other end being attached to the turned over edge of the guard 56, tends to hold the guard yieldingly 55 in contact with the end guard 52 and to hold the two guards against the ways 28. Adequate protection is provided for the rear end 60 of the ways 28 by a single guard 64 which is pivoted at 66 to the rear end of the wheel 65 spindle carriage 26 and is slidingly support-

ed on the fixed portion of the machine by the engagement of the turned over edges of the guard with rolls 68 mounted on each side of the machine base.

With the grinding wheel spindle carriage 70 retracted to the limit of its movement away from the work, the rear guard 64 will be permitted to hang in a substantially vertical position as its pivotal support 66 is moved to the rear of the rolls 68. The guards 52 and 75 56 at this time will occupy an extended position, the guard 56 which is carried rearwardly with the carriage 26 being held tightly against the upper edge of the lower guide 52 resting on the forward ends of the ways 28 80 by means of the tension spring 60. As the wheel spindle carriage is advanced during the grinding operation, the rear guard 64 will be drawn forwardly with the carriage being supported on the rolls 68. As the pivot 58 for the forward guard 56 is advanced, the guard is held at all times in contact with the lower guard 52 by the pressure of the spring 60. In the most advanced position of 85 the carriage, as shown in Fig. 2 of the drawings, the lower guard 52 has been swung forward beyond center by engagement with the projecting portions of the wheel spindle carriage 26 and rests yieldingly against the upper guard 56 which is held in its limiting vertical 90 position by the spring 60.

The invention having been described, what is claimed is:

1. A grinding machine having, in combination, a work table, a grinding wheel, a wheel spindle carriage, a water trough between the table and carriage, a bed provided with ways for the carriage and guards to prevent the water from coming in contact with the ways comprising a guard pivotally mounted on the machine frame adjacent the edge of the water trough, and a guard overlapping therewith in all positions of the carriage pivotally mounted on the carriage. 105

2. A grinding machine having, in combination, a work table, a grinding wheel, a wheel spindle carriage, a water trough between the table and carriage, a bed provided with ways for the carriage and guards to prevent the water from coming in contact with the ways comprising a guard pivotally mounted on the machine frame adjacent the edge of the water trough, a guard overlapping therewith in all positions of the carriage pivotally mounted on the carriage, and spring means 110 for holding the guards yieldingly in contact. 115

3. A grinding machine having, in combination, a work table, a grinding wheel, a wheel spindle carriage, a water trough between the table and carriage, a bed provided with ways for the carriage, and guards to prevent the water from coming in contact with the ways comprising a guard pivotally mounted on the carriage and projecting over 125 130

the ways at one end of the carriage, and a guard pivotally mounted on the carriage and projecting over the ways at the other end of the carriage.

5 4. A grinding machine having, in combination, a work table, a grinding wheel, a wheel spindle carriage, a bed provided with ways for the carriage, a water trough between the table and the carriage, and guards
10 to prevent the water from coming in contact with the ways and underlying parts comprising a guard extending laterally of the machine across the forward end of the carriage pivotally mounted on the machine frame adjacent the edge of the water trough and supported in a substantially upright position against adjacent portions of the machine, a guard overlapping therewith in all the positions of the carriage pivotally mounted on
15 the carriage, and spring means acting on the latter guard to hold the guards yieldingly in contact with each other and with underlying portions of the machine.

20 In testimony whereof I have signed my
25 name to this specification.

MAXWELL I. MATHEWSON.
